UNITED STATES PATENT OFFICE

ROY BRENHOLTS, OF COLUMBUS, OHIO

COMBINATION BENCH AND TABLE

Application filed January 11, 1930. Serial No. 420,240.

This invention relates to a combined table and seat and is particularly adapted for use in connection with restaurants, lunch rooms and other eating places.

5 In the present day method of serving lunches, wherein time saving is an important factor to be considered, the use of a table which may be converted from the ordinary height to an elevated position enables 10 self-service to be effected and eliminates the necessity of seats or benches thereby permitting ready access and egress to and from the table, thus serving as a counter. On the contrary when dinner is desired, the table may 15 be lowered and guests seated in the ordinary manner.

The primary object of the present invention lies in the provision of a combination table and seat of this character which 20 is so constructed that it may be readily converted from a low into a high table with a seat or seats swung from active positions at the sides of the table to inactive positions rearwardly and out of the way, permitting 25 the user of the table to occupy a standing or seated position at said table.

Another object of the invention resides in the provision of a new type of furniture of the aforesaid character embodying a table 20 having a movable top and shiftable seats attached thereto so that upon the manipulation of the table the seats are automatically swung to either active or inactive positions. The means connecting the table and benches 25 is so arranged as not to interfere with the feet of the persons occupying the benches or seats or obstruct the passage between the table and seats.

With these and other objects in view, which 40 will appear as the description proceeds, the invention consists in the novel features of construction, combination of elements and arrangement of parts hereinafter to be more fully described and pointed out in the appended claims.

In the accompanying drawings:

Figure 1 is a perspective view of the table and seats comprising the present invention,

50 Figure 2 is a view in side elevation of the table in its elevated position,

Figure 3 is a similar view showing the table in its lowered position,

Figure 4 is an enlarged vertical transverse sectional view taken through the table and the associated bench,

55 Figure 5 is a vertical sectional view taken on the line 5—5 of Figure 4,

Figure 6 is a similar view taken on the line 6—6 of Figure 4,

Figure 7 is a horizontal sectional view 60 taken on the line 7—7 of Figure 1.

Referring more particularly to the drawings, the numeral 1 designates my improved combination table and seats in its entirety and which table and seats in this instance 65 are arranged with one of their ends along the wall structure 2 with the seats or benches 3 at the sides of the table.

With reference to the construction of the table, the top 4 thereof is supported by frames 70 or legs 5 which have their lower ends enlarged to form feet 6 which are connected by a longitudinal tie member or rod 7. The upper portion of the supports or legs 5 are also connected by a similarly arranged tie 75 member 8 which together with the member 7 serves to hold the end frames in a rigid spaced relation. If desired, the end frames of the table may be anchored or secured to the floor in any suitable manner to prevent 80 shifting of the table during the raising or lowering thereof relative to the floor.

Depending from the under side of the table top 4 and positioned near the ends thereof are transversely disposed rails or braces 9 85 which have their lower edges hingedly connected as at 10 to floating or swinging leaves 11 which in turn are hingedly connected as at 12 to the upper ends of the end frames or leg members 5. When the table top 4 is in its lower position as shown in Figures 3 and 5, the leaves 11 are disposed between the rails 9 and the leg members 5 in a depending vertical position. The hinged arrangement of the leaves 11 is such that the latter 90 will swing outwardly and upwardly upon the raising of the table top 4 until the leaves are vertically aligned with the leg members 5 of the table. The arc of swinging movement 95 of the leaves 11 is indicated by dotted lines 100

in Figure 2. It will be seen by reference to Figure 5 that due to the novel arrangement of the hinges 10, the leaves 11 can only break in an outward direction away from the wall 2. However, the position of the table relative to the wall 2 may be such that the table top will engage therewith and which wall may thus act as a stop to the table top in an inward direction when the table occupies an elevated position. To prevent accidental collapse of the table, there is provided a brace 13 having its upper end hinged as at 14 to the inner of the rails 9 and the lower end positioned within a notch 15 formed in the upper edge of the tie member 8. It will be understood that when it is desired to lower the table it is only necessary to raise the lower end of the brace 13 from out of engagement with the notch 15 and give the table an outward pull which will swing on the leaves 11 until the top 4 occupies the position disclosed in Figure 3. If desired, the wall 2 may be provided with a shelf 16 in alignment with the top 4 when in a lowered position, so as to close up the space between the wall and the edge of the table.

In order to effect the automatic operation of the benches with the table top there is positioned for vertical sliding movement an inverted T-bar 17, which has its vertical leg 18 slidably positioned within a bearing member 19 secured to the wall 2. The upper end of the leg 18 is formed with an inward extension 20 to which the lower end of a link 21 is hinged. This link, which is inwardly inclined, has its upper end hingedly connected to the under side of the table top 4. It will thus be seen that as the table is raised or lowered the bar 17 will thus slide up or down in a vertical plane. The extension 20 is of sufficient width to insure the clearance of the shelf 16 when the table is raised to its elevated position.

Each of the benches 3 comprises a top or seat 22 hinged along one of its edges to back rests 23 which may be of any desired height. The outer free edges of the seats are supported by leg members 24 which have their upper ends hinged as at 25 to the seat 22 and the lower end engaging the post members 26 forming part of the back rest 23. The legs 24 are arranged on an incline to provide a wider aisle between the table and the benches and to prevent the obstruction of the passage therebetween. The inner leg members 24 are provided with pins 26' which are received within openings provided in the outer ends of the horizontal portion 27 of the T-bar 17. It will thus be seen that if the T-bar 17 is raised by the operation of the table top the seat 22 due to its connection with the portion 27 will swing on its hinge and lie vertically against the back rest 23.

As the pins 26', forming a connection between the bar 17 and the leg members 24,

move in a vertical plane the lower end of the legs 24 will slidably engage the surface 28 of the back rest 23 and occupy a substantially vertical position when the seats of the benches are elevated. The outer of the leg members 24 may have their lower ends provided with headed studs 29 which are slidably received within guides 30. This connection assures the engagement of the leg members with the surface 28 during the raising and lowering of the benches. If desired, a guard member 31 may be positioned to cover the lower portion of the bar 17 thus hiding the operating mechanism and adding to the general appearance of the table. Each end of this guard member is provided with a vertical slot 32 through which the pins 26' extend.

In operation it will be observed that if it is desired to raise the table top to an elevated position it is merely necessary to give the table an outward and upward lift which results through the mechanism connecting the table and the benches in the upward swinging movement of the benches to inactive positions.

From the foregoing it will be seen that there is provided a table structure which may be very conveniently and easily converted when desired, from a low to a high table and which serves the double purpose of a lunch counter as well as an ordinary dining table.

It will be obvious that the invention may be used for various purposes, and may have a single bench instead of two and that other changes may be made without departing from the spirit and scope of the invention as expressed in the appended claims.

What is claimed is:

1. A table of the class described, formed to comprise a pair of supporting legs, a top for said table, and rails positioned on the under side of said top, swinging leaves hingedly connected to the lower edges of said rails and the upper edges of said supporting legs, whereby upon the lifting of the table top said leaves will swing so as to form extensions for said supporting legs.

2. A table of the class described, formed to comprise a pair of end supports, a table top capable of being raised and lowered, and rails provided on the under side of said top and arranged on the corresponding sides of the respective supports, movable leaves having their upper edges hinged to the upper ends of said supports and their lower edges hinged to the lower edges of said end rails, said leaves being positioned between the rails and the upper ends of said supports when the table top is in its lowered position, and when swung with said top to a raised position said leaves will then be positioned in vertical alignment with said supports and rails.

3. A table of the class described, formed to comprise a pair of end supports and a movable top therefor, a rail at each end of said top and positioned on the under side thereof, 5 a hinged leaf connecting each rail and the upper ends of said supports and mounted for swinging movement from the sides of the supports to a position in alignment with the latter when the table is moved to a raised 10 position, and means carried by the under side of said top to prevent accidental collapse thereof when in a raised position.

4. A table of the class described, formed to comprise a pair of end legs united by a 15 longitudinally extending tie member, a table top supported by said legs, a rail at each end of said top and positioned on the under side thereof, a hinged leaf connecting each of said rails with the upper ends of said legs and 20 mounted for swinging movement from the sides of the legs to a position in alignment with the latter when the top is moved to a raised position, a brace hingedly carried by the under side of said top and having its 25 lower end engaging a notch formed in the upper end of said tie member, said brace serving to prevent accidental collapse of said top.

In testimony whereof I affix my signature.

30 ROY BRENHOLTS.
